UNITED STATES PATENT OFFICE.

JOHN A. SEAMAN, OF CHICAGO, ILLINOIS.

MACHINE FOR TRUSSING BARRELS.

SPECIFICATION forming part of Letters Patent No. 376,487, dated January 17, 1888.

Application filed September 21, 1886. Serial No. 214,167. (No model.)

To all whom it may concern:

Be it known that I, JOHN A. SEAMAN, of Chicago, county of Cook, and State of Illinois, have invented certain new and useful Improvements in Machines for Trussing Barrels, of which the following is a full, clear, and exact description, that will enable others to make and use the same, reference being had to the accompanying drawings, forming a part of this specification.

This invention relates to an improved automatic machine for trussing kegs, barrels, and packages of a similar character, the same consisting of certain novel features in the construction, combination, and operation of the several parts, as will be hereinafter set forth in detail, and pointed out in the claims. The mechanism is arranged to support the package in a horizontal position, both ends being trussed horizontally.

Figure 1 is a plan or top view of a machine embodying my improved features; Fig. 2, a broken-away plan of the mechanism for shifting the friction-pulleys, and Fig. 3 a side elevation of the same with some of the parts removed. Fig. 4 is a vertical longitudinal section showing the package in a trussed position; Fig. 5, a transverse section in the plane 5, Fig. 4; Fig. 6, a longitudinal section in the plane 6, Fig. 5; Fig. 7, a longitudinal section in the plane 7, Fig. 1; Fig. 8, a transverse section in the plane 8, Figs. 1 and 7. Fig. 9 is a transverse section in plane 9, Fig. 1; Fig. 10, a transverse section in the plane 10, Fig. 1; and Fig. 11, a face view of one of the centering-heads; Fig. 12, a broken-away section of the centering-head in the plane 12, Fig. 11.

In the drawings, A A are two bed-timbers, forming the longitudinal part of the supporting-frame, and are placed at some distance apart, providing the space A'; and A², A³, A⁴, A⁵, and A⁶ are the parts or castings of the supporting-frame, mounted transversely on the bed or base timbers.

B B' are two horizontal endless screw-shafts running lengthwise with and arranged at a suitable height above the bed-timbers. These screw-shafts have a rotary, but not an endwise, movement, and have suitable journal-bearings in the ends of the transverse parts or castings of the supporting-frame, as shown in Fig. 1. The parts a a' of these shafts have a right-and-

left screw-thread, so that when rotated in one direction the trussing-heads move inwardly, and outwardly when the motion is reversed. 55

B² B³ are two cross-heads mounted upon the threaded parts of the shafts B B' and the hollow shafts B⁴ B⁵. The ends of these cross-heads are perforated and correspondingly threaded with relation to the shafts, so as to have a forward or backward movement, in accordance with the direction in which the screw-shafts are revolving.

The hollow shafts B⁴ B⁵ are arranged in the center of the machine between the screw-shafts 65 and lie parallel with the same. These hollow shafts have an endwise movement and are provided with bearings in the center of the transverse parts of the frame, as shown in Fig. 1. These hollow shafts are provided on their inner ends with the annular flange or face-plate a², to which are secured by bolts a¹², Fig. 4, the hollow cylindrical trussing or compressing heads C C. The rear or bottom ends of these heads are partly closed, leaving a circular opening somewhat less than their diameters, thus forming the annulus a³, (see Fig. 4,) the inner edges of which engage with the annular shoulder-extension x, formed on the hollow shafts and inner side of the face plate or plates 70 a², thus securing and firmly holding the trussing-heads in place and preventing the same from moving out of position in any direction.

The trussing-heads are provided near their central interiors with the annular shoulder a⁴, 75 which is adapted to engage with and set the quarter truss-hoops a⁵, as shown in Fig. 4. From the shoulder a⁴ outwardly the diameter of the trussing-heads is increased, so that the front edge of the same will pass over, clearing 80 the quarter-hoops, and engage with the bilge truss hoops a⁶. The head or end truss-hoops, a⁷, are set up by means of the annular projecting rim a⁸, formed on the edge of the centering-heads C C', as shown in Figs. 4 and 12. 85 The ends of the staves forming the package pass just inside of the rim a⁸ and are brought to an even bearing against the centering-heads 90 during the operation of trussing.

The trussing or compressing heads may be 90 provided on the interior with a number of annular shoulders, as a⁴, in accordance with the number of truss-hooks on different packages.

The trussing-heads C C and the cross-heads

$B^2 B^3$ are connected by the brace-bars $b^2 b^3$, as shown in Fig. 1. These bars serve to stiffen and steady the movements and operation of the parts to which they are attached.

5 The centering-heads $C' C'$ are adapted to have an independent movement and adjustment relative to the trussing-heads, and are mounted on the inner ends of the solid companion shafts $C^2 C^2$ and rigidly secured thereto by means of suitable adjusting set-screws, c^2 . These centering-heads are each provided with four angle spring-arms, b , which are set quartering, as shown in Fig. 11. The inner ends of these spring-arms are rigidly secured to the centering-heads $C' C'$, the opposite ends being loosely inserted in the enlarged apertures b' of the same, as shown in Figs. 4 and 11, to permit of a slight movement of the spring when the latter is pressed upon. The loose ends 20 of these spring-arms pass just inside of the ends of the package, (see Fig. 4,) and exert a slight outward pressure against the interior of the same at as many different points as there are arms. The object of these spring-25 arms is to provide self adjusting and yielding bearings for the support and centering of the package, the spring-arms yielding to the action of the compressing-heads, and thus preventing the package from being damaged. This construction and operation imparts to the centering-heads the function of spring-heads as well.

The solid companion shafts $C^2 C^2$ have an independent endwise movement on the inside of the hollow companion shafts $B^4 B^3$. The outer projecting ends of the shafts $C^2 C^2$ have the split bearing-collars b^4 , provided with screws b^{12} , which draw the split parts together and bind the collar in place upon the shaft.

By forcing the walls of the split portion apart 40 by means of the screws b^{12} the position of the collars may be adjusted upon the shaft C^2 , as shown in Figs. 1 and 4. The upper bifurcated ends of the reciprocating vertical levers $b^5 b^5$ engage loosely with the flattened surface of 45 said bearing-collars, so as to insure a free endwise movement of the shafts $C^2 C^2$ and prevent binding or cramping. The lower ends of these levers are provided with the pivotal bearings b^6 (see Fig. 4) on a line with the base of the 50 frame.

The outer ends of the horizontal connecting-55 rods $C^3 C^3$ are attached to the vertical levers $b^5 b^5$ at a point near their longitudinal center, the inner ends curved and attached to opposite sides of the disk-wheel C^4 , mounted on the horizontal transverse rock-shaft C^5 , as shown in Figs. 1, 4, and 5. The rods $C^3 C^3$ are located in the space between the carriage or frame, as shown in Fig. 5. The rock-shaft 60 C^5 is supported at each end in the bearing block or blocks C^6 , loosely inserted in the elongated recess or recesses C^7 , located in the lower part of the frame, as shown in Figs. 5 and 6. The springs C^8 are arranged on each 65 side of the bearing-block C^6 , so that the latter may yield in either direction. The object of this construction is to allow these parts to au-

tomatically adjust themselves in unison with the spring centering and trussing heads, so as to conform to any irregularities.

The hand-operating lever C^9 (see Figs. 1 and 5) is rigidly secured to one end of the rock-shaft C^5 . By throwing this lever over to the right the centering-heads are moved in the direction of each other from the trussing-heads, as shown in Fig. 1. When thrown over to the left, the heads are returned to their normal position inside of the trussing-heads.

The transverse parts or castings $A^2 A^3 A^4$ of the frame project beyond the carriage on one side, as shown in Fig. 1, and provide bearings in the outer ends thereof for the driving shaft D , on which is mounted the ordinary friction-clutch mechanism, (see Figs. 1 and 7,) consisting of the band-pulleys $D' D'$, belted from the motive power so as to rotate in opposite directions, and the double cone-pulley D^2 , adapted to engage alternately with the correspondingly-beveled or conical interior surface of the band-pulleys. The normal 90 position of the double cone-friction is midway between the driving-pulleys, and is then out of engagement, the machine being at rest.

The bifurcated end of the bracket-arm D^3 (see Figs. 1 and 8) is connected to the hub of the friction-cones, the opposite end being secured on the horizontal shifting-rod D^4 , supported in the frame and adapted to have an endwise adjustment or movement. D^5 is a hand shifting-lever pivoted at the lower end to the collar d , mounted on the rod D^4 , as shown in Fig. 3, which is a reversed view looking from the inner side of Figs. 1 and 2. This lever is also pivoted to the fulcrum-arm d' , the opposite end of which is secured to the part A^4 of the frame. By means of this lever the rod D^4 can be moved endwise in either direction, thus imparting a corresponding movement to the friction-cones and throwing them into or out of engagement with the driving-pulleys, as may be required in operating the machine.

The companion shifting-rod D^6 is arranged at some distance from and parallel with the rod D^4 . d^2 is a collar placed upon the inner end of the rod D^4 , and d^3 a companion collar located opposite on the rod D^6 . These two collars are connected by means of the link D^7 , pivoted at each end to the same, as shown in Figs. 1 and 2. This link is also pivoted at or near its longitudinal center to the end of the fulcrum-arm d' .

The rod D^6 also has the two collars $d^5 d^6$ mounted thereon, and so located as to bring the cross-head B^2 on a line between them. To the under side and end of said cross-head, and next to the rod D^6 , is rigidly bolted one end of the automatic shifting-arm d^7 , (see Fig. 10,) the opposite fork end loosely embracing that portion of the rod D^6 between the said collars. By this means an automatic endwise movement is imparted to the rod D^6 , first in one direction and then in the other, as the arm d^7 is alternately brought in contact with the collars $d^5 d^6$, in accordance with the direction in which the cross-head B^2 is moving.

The movement of the rod D^6 causes the companion rod D^4 to move in the opposite direction through the medium of the connecting-link D^7 , thus automatically throwing the friction-cones out of or into engagement, as may be required in changing the direction and movement of the trussing mechanism.

All the collars mounted on the companion rods D^4 D^6 are secured by set-screws d^{12} , so that the same may be adjusted and set at any desired point as packages of different lengths may require.

The machine may also be started, stopped, or reversed by means of the hand-lever D^5 , connected to the rod D^4 .

The pinion d^8 is mounted on the driving-shaft D (see Figs. 1 and 9) and engages with the gear-wheel E , mounted on the counter-shaft E' , carrying the pinion e , which in turn engages with the gear-wheel E^2 , mounted on the end of the screw-shaft B . The gear-wheel E^2 next engages with the idler gear-wheel E^3 , provided with a suitable bearing and mounted on the hollow shaft B^4 , the idler-wheel E^3 engaging with the gear-wheel E^4 , the last of the train, and mounted on the screw-shaft B' . This train of gearing transmits the required motion from the driving-shaft to the companion screw-shafts.

The two vertically adjustable rests F (see Figs. 4 and 5) are secured opposite each other to the inner sides of the bed-timbers, and serve the purpose of supporting the package in position until picked up by the trussing mechanism.

The operation of the machine is as follows: The package to be trussed is placed in the machine on the supporting-rests. The hand-lever C^9 is now thrown over to the position indicated in Fig. 1, which has the effect of moving the centering-heads out from the trussing-heads to engage with the package. The spring-arms pass inside of and assist in supporting the same in a proper central position for the action of the trussing-heads. Power is imparted to one of the pulleys D' to rotate the shaft D and pinion d^8 , which rotates, by means of gear-wheels E , e , E^2 , E^3 , and E^4 , the screw-shafts B and B' , and these shafts, by means of cross-heads B^2 and B^3 , move the trussing-heads forward to inclose both ends of the package, the edges coming in contact with and driving the bilge-hoops, the interior shoulder, a^4 , performing a similar service for the quarter-hoops. The end or head hoops are set up by the bottom of the trussing-heads, bearing against the centering-heads, as illustrated in Fig. 4, which shows the package in a trussed position. The motion of the machine is now reversed by the cross-head B^2 contacting with collar d^6 and moving the rod D^6 forward to reverse the position of lever D^7 , which forces the rod D^4 and bracket backward and compels the cone D^2 to enter the other pulley, and the trussing-heads recede and return to their normal position. The hand-lever C^9 is next thrown over to the left or opposite position

from that illustrated in Fig. 1, which has the effect of withdrawing the centering-heads and returning them to the inside of the trussing-heads, leaving the package free to be rolled out of the machine to receive the permanent hoops. By this arrangement both ends are trussed simultaneously, the operation being so gradual as to produce a uniform and evenly-trussed package in all cases.

Packages of various sizes may be trussed in the same machine by having a corresponding number of compressing and centering heads of different diameters.

Having thus described my invention, what I claim as new, and desire to secure by Letters Patent, is—

1. In a barrel-trussing machine, the combination of two endless rotating screw-shafts on opposite sides of the machine and having right and left hand screw-threads on opposite ends, respectively, the cross-heads B^2 and B^3 at opposite ends of the machine, and having correspondingly screw-threaded engagement with said screw-shafts, the hollow shafts B^4 and B^5 , on which the cross-heads are mounted, and having the trussing-heads C , and the reciprocating shafts C^2 , inclosed by the hollow shafts, and having the centering-heads C' , substantially as described.

2. In a barrel-trussing machine, the combination, with a hollow shaft having an endwise movement only and provided with the face-plate a^2 and the annular shoulder x , of a cylindrical trussing-head adapted to be removably secured to said face-plate and having the annulus a^3 , which engages with the shoulder x , the reciprocating shafts C^2 , and the centering-heads having an annular projecting rim, substantially as set forth.

3. In a barrel-trussing machine, the combination of a hollow compressing-head of variable diameter and having an annular shoulder, a^4 , at or near the central interior, and annulus a^3 at the rear or bottom end, and a centering-head within the compressing-head, having the annular projecting rim a^8 , substantially as described.

4. In a barrel-trussing machine, the combination of two endless screws, the compressing-heads, the cross-heads connected with said compressing-heads, the hollow shafts having an idler gear-wheel connecting the gear-wheels of the endless screws, the centering-heads having the reciprocating shafts within said hollow shafts, and the pulleys connected with said gearing and having a friction-clutch for reversing the motion of the gearing, substantially as described.

5. In a barrel-trussing machine, the combination, with the compressing-heads, of the centering-heads C' , having the annular projecting rim a^8 and a number of apertures, b' , and the angle spring-arms b , the inner ends of which are rigidly secured to the hub of said head C' , while the outer ends are loosely inserted in said apertures, substantially as described.

6. In a barrel-trussing machine, the combination, with a trussing-head adapted to set up or drive the bilge and quarter hoops, of a centering-head provided with the springs forming a yielding support for the end of the barrel, and the annular rim a^8 , which bears against the end or head hoop and drives the same by reason of said trussing-head forcing said centering-head inward, substantially as set forth.

7. In a barrel-trussing machine adapted to truss both ends of a package simultaneously, the combination, with the compressing-heads $C^2 C'$, of the centering-heads $C' C'$, having the springs which form a yielding support for the barrel and co operating with said compressing-heads, but having an independent action relative thereto, substantially as and for the purpose set forth.

8. In a barrel-trussing machine, the combination, with the solid companion shafts $C^2 C^2$, having an endwise movement, of the centering-heads mounted on the inner ends of said shafts and having springs which form a yield-

ing support for the barrel, the reciprocating levers b^5 , the upper ends of which are adjustably secured to the outer ends of said shafts, and the lower ends provided with a pivotal bearing, the connecting-rods $C^3 C^3$, the disk-wheel C^4 , the rock-shaft C^5 , and the hand-lever C^6 , whereby the centering-heads are operated by hand independently of the trussing-heads, substantially as set forth.

9. In a barrel-trussing machine, the combination, with the cross-head B^2 , of the friction-cones, the driving-pulleys, the automatic shift- ing-arm d^4 , the rod D^6 , the collars $d^5 d^6$, the companion rod D^4 , the fulcrumed link D^7 , connecting said rods, and the bracket-arm D^3 , whereby the friction cone-pulleys are automatically and alternately thrown into and out of engagement relative to the driving-pulleys, substantially as and for the purpose set forth.
